(57) **CLAIM**

The ornamental design for a diabetic testing equipment organizer, as shown and described.

DESCRIPTION

FIG. 1 is a top, front, and right perspective view of a diabetic testing equipment organizer, showing my new design; FIG. 2 is a top, rear, and left perspective view thereof; FIG. 3 is a front elevation view thereof; FIG. 4 is a rear elevation view thereof; FIG. 5 is a right elevation view thereof; FIG. 6 is a left elevation view thereof; FIG. 7 is a top plan view thereof; and, FIG. 8 is a bottom plan view thereof.

The broken lines, the areas within them, and the areas surrounded by both broken lines and solid lines in FIG. 3 depict portions of the diabetic testing equipment organizer that form no part of the claimed design.
